UNITED STATES PATENT OFFICE.

EMMA J. LAWRENCE, OF PHILADELPHIA, PENNSYLVANIA, ASSIGNOR TO THE HARTLEY CARPET AND RUG COMPANY, OF SAME PLACE.

DESIGN FOR A RUG.

SPECIFICATION forming part of Design No. 16,883, dated August 31, 1886.

Application filed July 8, 1886. Serial No. 207,590. Term of patent 3½ years.

To all whom it may concern:

Be it known that I, EMMA J. LAWRENCE, a citizen of the United States, residing in Philadelphia, Pennsylvania, have invented a new and original Design for a Rug, of which the following is a specification.

My design for a rug is fully shown in the accompanying photographic illustration, exhibiting three-quarters of the length of the 10 design for the rug. The remaining quarter of the design being a duplicate of the end piece shown, it has not been deemed necessary to reproduce it in illustration.

My design comprises a center piece, A, and 15 border B, with a narrow intervening frame-like division, a, between the border and center piece. The grounds of the center piece and border are preferably of contrasting colors, and in the illustration I have shown the ground 20 of the center piece as of a dark color, while the ground of the margin is light. The center piece represents a conventional picture of a pond or other sheet of water, with pond-lilies in the water and leaves in the background, 25 and storks standing in the water at opposite sides and facing each other. On the border, at the ends and along one side, there are branches and leaves, with blossoms over the background and partially extending over the center piece, while along the other side of the 30 border are represented in conventional form the leaves and flowers of the pond-lily, alternating, the flowers being surrounded by curved stems.

I claim—

The herein-described design for a rug, comprising a center piece representing water with pond-lilies and storks, and a border having on the ends and on one side branches, leaves, and blossoms, and along the other side the 40 leaves and flowers of the pond-lily, alternating, substantially as shown and set forth.

In testimony whereof I have signed my name to this specification in the presence of two subscribing witnesses.

EMMA J. LAWRENCE.
